UNITED STATES PATENT OFFICE.

GRANGER SMITH, OF CHICAGO, ILLINOIS.

HASP-LOCK.

SPECIFICATION forming part of Letters Patent No. 254,397, dated February 28, 1882.
Application filed November 4, 1881. (No model.)

To all whom it may concern:

Be it known that I, GRANGER SMITH, of Chicago, in the county of Cook and State of Illinois, have invented certain new and useful improvements in Staples for Hasps; and I do hereby declare that the following is a full, clear, and exact description thereof, reference being had to the accompanying drawings, and to the letters of reference marked thereon, which form a part of this specification.

This invention relates to staples for hasps and other purposes, and has for its objects to enable the staple to be applied with greater ease, to avoid the dangers of splitting the part to which the staple is applied, and of bending or breaking the staple in applying the same, which accompany the use of staples that require to be driven; also, to give greater security to the staple when applied, and particularly to guard against its removal when used in connection with a hasp and lock.

To these ends said invention consists, first, in a staple having one long and one short leg, the longer leg being screw-threaded, and the shorter leg being provided with a foot intended to rest on the surface of the part to which the staple is applied, and apertured to receive a separate screw; and, second, in the combination, with a hasp, of a staple having one of its legs the longer and screw-threaded, and the other and shorter leg provided with a foot intended to rest on the surface of the part to which the staple is applied, and beneath the hasp when the latter is in place thereon.

In the drawings, Figure 1 is a perspective view of the more approved form of the staple detached. Fig. 2 is an elevation of two staples containing my improvement, shown in connection with a hasp in place thereon, and the whole applied, as to a door and post. Fig. 3 is a perspective view of the matters shown in Fig. 2. Fig. 4 shows the foot upon the short leg of the staple let into the face of the wood flush therewith. Fig. 5 shows the eye of the staple closed at the base.

A is a staple, of which α is the eye. B is a hasp, having a slot, b , and eye b' . As shown in Figs. 1 to 5, the staple has one long screw-threaded leg, C, and one short leg, D, provided with the foot E. Said foot is preferably apertured and countersunk to receive the separate ordinary screw, F.

In applying a staple so constructed to a door-post, to be used in connection with a hasp, B, the threaded leg C is run into the wood until the foot E strikes the surface. It is then adjusted so that the eye a will enter the slot, the foot being brought to the inner end of the slot, so as to be covered by the body of the hasp when in place upon the eye. When a padlock is applied to secure the hasp in this position over the staple it is evident that the head of the screw F, if employed, is inaccessible, and also that the screw C cannot be turned. The construction shown therefore affords much greater security than is found in staples of the ordinary forms, while it is not subject to spreading or liable to split the board to which it is applied, as is the case with staples which require to be driven. The similar staple applied to the door and used to permanently hold the hasp thereto by its eye b' is also arranged with its foot beneath the hasp, as clearly indicated in the drawings.

In Fig. 4 the foot E is shown let into the wood flush with its face, so that the hasp lies flat over both. This effect is produced by turning in the leg C the proper distance, and then bending in the short leg D and foot E to the position shown.

It is evident that the staple described is relatively easy of application, since the eye a and foot E afford ample leverage and hold for the hand, or for a rod, or the hasp employed as a wrench, to run in the threaded leg C. Said leg being arranged at the outer end of the hasp-slot and in line with the outer part of the eye a , moreover, no shoulder is exposed beneath which a lever or claw can be inserted to draw the screw.

It is plain that in the use of the staples with a hasp the second screw, F, is not strictly essential, except to prevent the staple from being turned when the hasp is removed, since the foot E extends beneath the hasp and prevents the bending out of the short leg D when the hasp is locked thereon. The screw F is of course a re-enforcement of the screw C, and also operates to prevent the latter from being broken off by bending outward when the hasp is removed.

A nail may be used in place of the screw F, with equal effect, to prevent rotation of the staple in the absence of the hasp.

If the screw or nail F be omitted, the staple is held from turning when embraced within the hasp-slot by reason of the broad bearing of the staple-eye a at its base in said slot.

When the staple is of malleable iron the legs may be joined by the connection a' to give a closed eye and greater strength.

I claim as my invention—

1. The staple described, having its longer leg, C, screw-threaded, and its shorter leg, D, provided with a foot, E, apertured to receive a screw, F, substantially as described.
2. In combination with a hasp, the staple

described, having one of its legs the longer and screw-threaded, and the shorter leg provided with a foot intended to rest on the part to which the staple is applied, and to be arranged to extend beneath the hasp when the latter is in place thereon, substantially as described.

In testimony that I claim the foregoing as my invention I affix my signature in presence of two witnesses.

Witnesses: GRANGER SMITH.
